UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 14,564, dated December 25, 1883.
Application filed July 23, 1883. Term of patent 24 years.

To all whom it may concern:

Be it known that I, WINTHROP L. JACOBS, of East Orange, New Jersey, have invented a new and original Design for Carpets, of which 5 the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

15 The ground *a* is a plain ground having at irregular intervals and in groups right-lined geometric work, partly filling the spaces between the large flower-groups.

A is a large open flower and leaf group consisting of a central cluster of star-shaped flowers resting on a mass of large leaves, and surrounded by leaf and flower sprays jutting out loosely over the ground *a*. B is a large open flower and leaf group, also consisting of a central mass and loose jutting sprays of leaf and blossom. Several other smaller flower and leaf groups complete the design, which is all clearly shown in the photograph.

I claim—

The design for a carpet, substantially as shown and described.

WINTHROP L. JACOBS.
